US00D847969S

(12) **United States Design Patent** (10) Patent No.: **US D847,969 S**
(45) Date of Patent: ** May 7, 2019

(54) **FAN CANOPY**(71) Applicant: **DELTA T CORPORATION**, Lexington, KY (US)(72) Inventors: **Ernest John Noble**, Selangor (MY); **Ken Siong Tan**, Selangor (MY); **Jon Jet Ling**, Selangor (MY); **Seng Rui Chan**, Selangor (MY)(73) Assignee: **DELTA T, LLC**, Lexington, KY (US)(**) Term: **15 Years**(21) Appl. No.: **29/550,461**(22) Filed: **Jan. 4, 2016**(51) LOC (11) Cl. **23-03**

(52) U.S. Cl.

USPC ..... **D23/411**(58) **Field of Classification Search**

USPC D23/385, 397, 398, 403, 405, 407, 411, D23/415

CLAIM

The ornamental design for a fan canopy, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a bottom perspective view of a first embodiment of a fan canopy;

FIG. 2 is an enlarged perspective view of the first embodiment of the fan canopy;

FIG. 3 is a front view of the first embodiment of the fan canopy;

FIG. 4 is a right side view of the first embodiment of the fan canopy;

FIG. 5 is a rear view of the first embodiment of the fan canopy;

FIG. 6 is a left side view of the first embodiment of the fan canopy;

FIG. 7 is a top view of the first embodiment of the fan canopy;

FIG. 8 is a bottom view of the first embodiment of the fan canopy;

FIG. 9 is a bottom perspective view of a second embodiment of the fan canopy, with a portion indicated as being in the color blue;

FIG. 10 is an enlarged perspective view of the second embodiment of the fan canopy;

FIG. 11 is a front view of the second embodiment of the fan canopy;

FIG. 12 is a right side view of the second embodiment of the fan canopy;

FIG. 13 is a rear view of the second embodiment of the fan canopy;

FIG. 14 is a left side view of the second embodiment of the fan canopy;

FIG. 15 is a top view of the second embodiment of the fan canopy; and,

FIG. 16 is a bottom view of the second embodiment of the fan canopy.

The broken lines shown in the drawings illustrate the fan and portions of the fan canopy that form no part of the claimed design.
